UNITED STATES PATENT OFFICE

2,587,772

WATER COOLER

Arthur Seligman, Newark, N. J.

Application July 12, 1949, Serial No. 104,251

4 Claims. (Cl. 62-125)

1

This invention relates to a refrigerating system with a secondary cycle whose condenser is cooled by a primary source of cold, as e. g. a substance, or mixture of substances melting or evaporating at low temperature; usually this substance is recirculated in a closed primary refrigerating cycle, which may consist of any of the conventional systems, compression or absorption, and may use any of the conventional refrigerating media.

The secondary cycle is very simple in its design, having no compressor or absorber, but using gravity as motive power for the circulation of the refrigerant, and it is characterized by the fact that its evaporator temperature is higher than its condenser temperature. A variety of substances may be used as refrigerants in the secondary cycle; they must, however, be selected so as to conform to certain requirements, as will be explained later.

The object of the invention is the removal of heat within a limited range of temperature, that is at a temperature low enough to accomplish the purpose of the cooling operation, but never below a safe degree, regardless of possible wide variations of the evaporator temperature of the primary cycle, and regardless of the amount of heat withdrawn in the secondary evaporator. The invention may be used, but is, of course, not restricted, to combine a water cooler with a household or a small commercial refrigerator. In these refrigerators trays for freezing ice cubes are usually provided, and in many cases also low temperature storage compartments; the evaporator temperature must, therefore, be kept considerably below the freezing point of water; even without these accessories the desire to avoid excessively large cooling surfaces would call for a low evaporator temperature; the standard practice is, therefore, to operate the evaporators at about 18° F.

On the other hand, in water coolers the evaporator temperature must be kept slightly above 32° F. to avoid the formation of ice.

It is, thus, not possible to use a part of the evaporator of a refrigerator directly for water cooling. Even if the heat exchanging surface were made very small, or if an obstacle were put in the path of heat transfer, such as a layer of material of low conductivity, the danger of a freeze-up could still not be eliminated in case no water were withdrawn for a considerable length of time. If the water cooler were not in direct contact with the evaporator, but placed within the refrigerator in heat exchange with the cold air, freezing would be avoided, in as much as the cabinet temperature is usually kept above 32° F.; but the heat transmission coefficient from still air is so low that a very large surface would be needed to attain sufficient capacity.

The present invention allows to build a water cooler in combination with a refrigerator, which has a good heat transfer to insure a satisfactory

2

chilling when a large number of drinks is taken in rapid succession, and which yet is absolutely safe against freezing when no water is withdrawn for any length of time.

5 The accompanying drawings illustrate the principle.

Fig. 1 shows a section through the essential parts of the device, serving as a water cooler integrated in a household refrigerator, whereas Fig. 2 shows in section another variation of the device proper only, i. e. with all other parts omitted except the primary evaporator coils.

Referring to Fig. 1, the water is supplied through pipe line 1 from an inverted glass jar 2; this is, of course, not essential to the invention; for instance, the line 1 may be directly connected to the city water supply, and, naturally, beverages other than water may be cooled just as well. The water passes through the coil

20 3, where it is chilled, and is withdrawn, as required, from the faucet 4. The coil 3 is located in the secondary evaporator 5 and immersed in the secondary refrigerant boiling therein, thus absorbing heat from the water. The refrigerant

25 vapors pass through the suction line 6 to the secondary condenser 7, where they are condensed by the primary source of cold, viz. a part of the coils of the primary evaporator 8. The liquefied refrigerant assembles in the receiver 9, which is located below the condenser and in unrestricted communication with it, until the liquid reaches the overflow 10, from which it flows through the liquid line 11 back to the secondary evaporator.

It will be noted that the last part of the suction line 6 is bent downward and that its open end 12 is near the bottom of the condenser receiver. The vapor on its way from the evaporator to the condenser must, thus, overcome a static head, which is determined by the immersion H, i. e. the vertical distance from the opening 12 of the suction line to the overflow 10. Thus, the pressure, and consequently the temperature in the evaporator must at all times be higher than in the condenser; when not enough

35 water passes through the cooler to bring the refrigerant to a boil under this predetermined pressure, evaporation and further chilling of the water will stop.

The primary evaporator 8 is, of course, a part 50 of the well known refrigerating system, whose "high side" 13 is not shown in detail, and whose accessories, such as thermostatic control, are omitted for simplicity's sake, as they are obvious to those familiar with the art. For the same

55 reason the insulation of the refrigerator is not shown. It may, however, be mentioned that the secondary evaporator may be arranged either inside the main insulation (it need not be insulated against the cabinet space, or only very slightly), or outside (and slightly insulated against the atmosphere), or it may be embedded in the main insulation.

It may be pointed out that the designer has a

great amount of freedom in locating the secondary evaporator. It is only required that the difference L between the liquid levels in receiver and evaporator is by a safety margin R greater than the immersion H to insure the return of the liquid, and that the highest point of the suction line is by a safety margin S higher than the overflow 10 to prevent back flow; the faucet 4 , of course, must be at a lower level than the water supply 2 .

In the variation shown by Fig. 2 the evaporator is placed in close vicinity to the condenser. Corresponding parts are marked with the same symbols as in Fig. 1. The water enters from a suitable supply through valve 14 , which, of course, can be kept open all the time during normal operation. A layer of insulating material 15 is provided to prevent direct heat exchange from the water to the cold liquid refrigerant in the condenser. In this case the boiling refrigerant is confined within the pipe coil of the evaporator, the water is in the outer shell, where suitable baffles may be arranged to guide it on a serpentine path; this arrangement is preferable where finned or bristled tubing is used, as for well known reasons the fins are to be on the side with the lower heat transfer coefficient.

It has been stated above that a number of refrigerants are available for the secondary cycle; the following discussion shows how for given operating conditions a proper substance may be selected and the principal dimensions of the apparatus may be determined.

It is assumed that a capacity of 100 B. t. u./hr. is required, that the secondary evaporator temperature be 40° F., and the condenser temperature 18° F. The three substances carbon-tetrachloride, ethyl-alcohol, and methyl-alcohol are to be investigated. For brevity's sake certain simplifications and approximations have been used in the following, which, however, do not essentially influence the result.

In the attached tabulation the values of freezing points, latent heats, and densities resp. as entered on lines 3, 6, and 8 were taken from competent handbooks. It is known that for most substances the relation between vapor pressure p'' and absolute temperature T can be expressed by the equation

$$(1) \quad \log p'' = a - \frac{K}{T}$$

wherein a and K are constants; by analyzing the experimentally found vapor pressures at various temperatures from the best available sources, values of these constants could be determined and entered on lines 4 and 5 resp. referring to inches of mercury and degrees Fahrenheit absolute as units. Therefrom the vapor pressures p'' at seven temperatures, which are of interest in this investigation were calculated. On lines 9 to 15 are tabulated the columns of liquid h of each substance equivalent to its vapor pressure at these seven characteristic temperatures; to get these figures from the vapor pressures is, of course, simply a matter of converting into another unit, viz.

$$(2) \quad h = \frac{p'' \times 850}{\gamma'_{22}}$$

wherein the figure 850 represents the specific weight of mercury. In the actual operation of the apparatus the temperature of the liquid line 11 is somewhere between the condenser temperature of 18° and the evaporator temperature of 40° ; inasmuch as the density of the liquid

varies very little between these limits, the error committed by using the density at 32° is negligible.

In the absence of direct experimental data the vapor densities at 40° were approximately calculated as though the substances were ideal gases, which is exact enough for the intended comparison; the density of an ideal gas is

$$10 (3) \quad \gamma = \frac{\mu \times p}{k \times T}$$

wherein k depends on the units and is 23.3 in our case; see line 7.

Now, by simply subtracting the liquid columns for the condenser temperature (line 11) from those for the evaporator temperature (line 14) the decisive figure for the design is arrived at, namely the height of the immersion H (line 16).

In order to investigate more closely the operating characteristics the gradients of the vapor pressure at the operating temperatures are given on lines 17 and 18, that is the variation of pressure for 1° F. variation of temperature, or mathematically speaking the first derivatives of the pressure with respect to the temperature, which are, of course, easily arrived at by differentiating Equation 1, namely

$$11 (4) \quad G = \frac{dh}{dT} = h \times \frac{K}{T^2} \times \ln 10$$

30 Comparing the gradients at 40° and 18° furnishes an important characteristic, as will be discussed later; see line 19. As stated above, the normal condenser temperature is supposed to be 18° , and the apparatus is so designed as to render the evaporator temperature 40° under this condition. It may now be investigated what happens when the condenser temperature varies. It may be assumed that the control of the primary cycle allows a decrease or increase of 4° , i. e. a variation from 14° to 22° . In as much as the pressure differential between condenser and evaporator must remain constant, namely H , it is simple to calculate the corresponding evaporator pressures, as indicated on lines 20 and 21. By means of either the gradient G_{40} or of Equation 1 the corresponding evaporator temperatures can easily be computed as shown on lines 22 and 23.

To avoid a freeze-up the evaporator temperature must not fall below 32° . The condenser pressures which would have to be reached in order to bring about this condition are listed on line 24, and the corresponding temperatures on line 25. It may be mentioned that the actual temperatures of the primary refrigerant would 55 have to be even lower than these figures to cause a freeze-up because of the necessary temperature drop on and through the heat exchanging surfaces.

The liquid column L must not only counter-balance the static pressure differential between evaporator and condenser, but also provide a slight excess to impart a sufficient velocity to the vapor in the suction line 6 and thus keep the system in motion. To create a velocity w a pressure drop of

$$60 (5) \quad \Delta p = \frac{w^2 \times \gamma''_{40}}{2 \times g}$$

is required, g being the acceleration of gravity. A velocity of 2000 ft./min. for instance would thus require a pressure drop of

$$65 \quad \Delta p_{2000} = \frac{2000^2 \times \gamma''_{40}}{3600 \times 2 \times 30} = 18.2 \times \gamma''_{40} \text{ lbs./sq. ft.}$$

The corresponding liquid columns are obviously

$$(6) \quad \Delta h = \frac{\Delta p}{\gamma'_{32}} \times 12$$

inches of liquid, or

$$(6a) \quad \Delta h = \frac{\gamma'_{40}}{\gamma'_{32}} \times 218.4$$

and are shown on line 26. While no claim to exactness can be made for these values, a comparison of lines 26 and 16 ascertains that the additional liquid head is only a negligible fraction of the total.

For the purpose of comparing the necessary size of the apparatus the volumes of vapor to be circulated for one B. t. u. refrigeration are given on line 27; it is obviously

$$(7) \quad v = \frac{1}{r_{40} \times \gamma'_{40}}$$

Finally on the last line the necessary diameters of the suction line are listed, assuming for comparison's sake a capacity of 100 B. t. u./hr. and a vapor velocity of 2000 ft./min.

We are now ready to discuss the selection of a proper refrigerant.

Within the contemplated working range the vapor pressures of ethylalcohol, methylalcohol, and carbontetrachloride, as computed by Equation 1 have a ratio of approximately 1:2:3. In as much as all of them, however, are of the magnitude of one inch of mercury, there is no decisive advantage on this count for any of the three substances, although the higher pressure of carbontetrachloride may be regarded as slightly favorable, because very small traces of air remaining after evacuation will be the more negligible the higher the partial pressure of the refrigerant.

Line 8 shows that the amount of refrigerant required to properly fill the system is about twice

as much for carbontetrachloride as for either of the alcohols. As only small quantities are involved and all three substances are rather common and cheap, this point will hardly influence the final choice. Also the fact that the alcohols are inflammable, whereas carbontetrachloride is not, will not be absolutely decisive in view of the small quantities and of the fact that the system is under vacuum.

10 As seen from line 16, the condenser must be located about twice as high above the evaporator in the case of methylalcohol as for either of the other refrigerants, which may be a disadvantage where a very compact construction is desired.

15 Line 19 shows that there is only a very small difference between the three substances with respect to sensitivity, that is to the variation of evaporator temperature for a given variation of condenser temperature. Line 25, however, shows that the ultimate safety margin is considerably better for methylalcohol than for carbontetrachloride, in as much as for a freeze-up the condenser temperature will have to fall abt. 9° deeper.

20 Line 27 finally reveals that ethylalcohol requires the circulation of a vapor volume about twice as large as the other two; this, of course, requires larger pipe lines, unless a higher velocity is resorted to, which seems admissible in view of the small pressure drop required to create it, as shown on line 26.

25 In summarizing it may be stated that all three substances under investigation proved to be suitable refrigerants for the system described. Each of them has slight advantages in some respect, which may make it preferable under certain condition, but none of them shows such a decisive advantage anywhere as to make it the best choice under all conditions.

I claim:

1. Method of controlling the evaporator temperature of a secondary refrigerating cycle in which a liquid refrigerant is evaporated to produce the cold, its vapors subsequently re-condensed at a higher level at lower temperature and pressure, and the liquid fed back to the evaporator by gravity, whereby a constant difference between condensing and evaporating pressures is maintained by passing the vapor on its way from evaporation to condensation through a column of the liquid refrigerant, which is held at a constant height.

2. Refrigerating apparatus, consisting of an evaporator, a receiver located at a higher level than the evaporator, a condenser located at a higher level than the receiver and in unrestricted communication therewith, a liquid return line leading from the top of the receiver to a point near the bottom of the evaporator, and a suction line leading from the top of the evaporator to a point higher than the top of the receiver and down again into the receiver near its bottom. 15 20

3. Refrigerating apparatus as specified in claim 2, in which the vertical distance H between the connections of the suction line and of the liquid return line to the receiver is so chosen as to create the desired pressure difference, and the vertical distance L from the connection of liquid return line and receiver to the top of the evaporator is at least of the same length.

4. Refrigerating apparatus as specified in claim 10 3, particularly for chilling aqueous fluids, in which said vertical distances are of sufficient height as to ensure an evaporator temperature above 32° F. at the lowest possible condenser temperature.
